G. C. SNYDER.

TIE KEEPER.

APPLICATION FILED JULY 28, 1917.

1,386,660.

Patented Aug. 9, 1921.

UNITED STATES PATENT OFFICE.

GEORGE C. SNYDER, OF NEW YORK, N. Y., ASSIGNOR OF ONE-SIXTH TO FRANK K.
HOFFMAN AND ONE-SIXTH TO E. THEO. I. THYGESEN, OF NEW YORK, N. Y.

TIE-KEEPER.

1,386,660.

Specification of Letters Patent. Patented Aug. 9, 1921.

Application filed July 28, 1917. Serial No. 183,224.

To all whom it may concern:

Be it known that I, GEORGE C. SNYDER, a citizen of the United States, residing at New York, in the county of New York, State of New York, have invented certain new and useful Improvements in Tie-Keepers; and I do hereby declare the following to be a full, clear, and exact description of the invention, such as will enable others skilled in the art 10 to which it appertains to make and use the same.

The present invention relates to tie-keepers and particularly to a device whereby package ties of the form illustrated in my 15 copending application, Serial No. 183,223 filed July 28, 1917, may be held in position ready to be removed without danger of the cords of the ties becoming tangled. The package ties shown in the application referred to above comprise fastening devices 20 and cords attached to them. Since these cords may be of considerable length and a large number of them may be gathered into a bundle from which they are drawn as de- 25 sired, the danger of the cords becoming tangled with each other is a serious one. Package ties of the form described above are especially adapted for use in postal service and any delay caused by tangling of the 30 cords would not be tolerated.

The present invention has for an object the provision of a member adapted to hold a bundle of such ties and in connection with this holder, means are provided to apply a 35 substantially uniform binding pressure about the cords of the ties so that when any one of the cords is removed, it must be drawn through the binding device while the tendency of any of the other cords to become tangled with the cord that is being withdrawn 40 is effectually prevented.

The construction, method of using and other advantageous features of the device of the present invention will appear from a detailed description of preferred embodiments 45 thereof, as shown in the accompanying drawing, in which Figure 1 represents a view of one form of the device, Fig. 2 is a detailed view in section through the means for fastening the device to a table or other support, and Fig. 3 is a view in transverse section showing a modified form of the device.

Referring to the drawings in which similar reference characters denote similar parts

throughout the several views, 10 is a table, shelf or other support upon which the device is to be mounted in position for convenient use. The device itself comprises inclined members 11 and 12 which are fitted together at their lower edges to form a V-shaped channel within which the cords 13 attached to the tying devices 14 may be placed. These tying devices 14 are shown as of the type disclosed in my copending application to which reference has been made above, but it will be understood that the usefulness of the present invention is not limited to package ties of this particular construction, nor, in fact, is it limited to 70 package ties alone for it may be used for holding cord lengths of any kind which might otherwise become tangled with each other as successively withdrawn.

The members 11 and 12 are in Fig. 1 attached to the upper ends of tapering supporting members 15. These supporting members are connected at their lower ends by a base piece 16 through which passes a bolt 17 provided with a wing nut 18 by which it 75 may be clamped to the supporting shelf or table 10, it being only necessary to provide a bolt hole 19 in the latter at the point where it is desired to attach the tie-keeper. By using a bolt having a squared portion near 80 its head, it will be unnecessary to provide any other means for preventing the bolt from turning in the member 16, but it will be understood, of course, that any other form of attaching device may be used. 85 Preferably but one bolt should be used in order to permit the device to be turned into any desired position, and in order to attach the device at any particular point, it will be necessary to provide only one bolt hole 19 in 90 the shelf or table.

In Fig. 3 a somewhat modified form of support for the inclined members 11 and 12 is shown. In this case the supporting members 15' do not taper at their lower ends as 100 do the members 15 of Fig. 1, and they are attached to a base plate 16' which is adapted to be attached to the table or shelf 10 by means of screws 17'. The form of the device shown in Fig. 3 is intended more especially for use in those places where the device after having been once attached to a shelf or table may be left permanently in 105 place, whereas the device of Fig. 1 is intended more particularly for use where the 110

demands of the service may require that it be placed at different points from time to time.

A cord 20 is attached to one of the members 11 or 12 at or near the apex of the V-shaped channel formed by these members. The mode of attachment shown in Fig. 3 is a simple one and eliminates any nut or fastening device on the inner face of either 10 of the members 11 and 12. A slot 21 is provided in the inclined member which is at the front of the device and this slot has such a depth with relation to the inclination of the members 11 and 12 that when a bundle 15 of tying cords of the usual size is placed in the channel formed by these members, the cord 20 will pass around the bundle of cords and hang freely through the slot 21. In order to produce a substantially equalized 20 pressure upon the tying cords, a weight 22 is attached to the end of cord 20, which should be of sufficient length to permit the weight to hang freely without interfering with the base of the device or the outer edge 25 of the supporting table or shelf. Whenever it is desired to remove the entire bundle of tying cords or place a new bundle of these cords in position for use, the weight 22 may be placed on the table or shelf 10 as indicated 30 in dotted lines in Fig. 3.

With the weight suspended, the cord 20 will exert a substantially uniform binding pressure about the tying cords at a point intermediate their ends, with the result that 35 any one of the tying cords may be withdrawn from the bundle without becoming tangled with the remaining cords. The provision of gravity actuated means for producing the binding effect permits a uniform 40 pressure to be obtained at all times and the use of a cord 20 has the advantage that there is less tendency to fray the tying cords as they are withdrawn than would be the case if a metallic wire, or spring were used for 45 producing the binding pressure. The invention however, is not to be regarded as restricted to the use of a fibrous cord, nor to the gravity control means for producing the pressure since it is obvious that the cord 50 may be made of other materials and that the production of the binding pressure about the tying cords may be produced by other agencies than gravity without departing from the principle of the invention. Neither

is the device to be restricted to the use of 55 inclined members meeting at their lower edges to form a V-shaped channel since the cords may be supported on corresponding members having different forms of channel between them, or in fact may even be supported upon a flat surface provided means equivalent to the cord 20 and weight 22 are provided for producing a substantially uniform binding pressure about the tying cords as shown in the illustrated embodiments of 60 65 the invention.

I claim:

1. In a keeper for fastening devices provided with tying cords, the combination of a channel member open at its ends for holding the cords, supporting means for the holding member comprising a pair of tapering members, a cross bar connecting the lower ends of the tapering members and means passing through the cross bar for attaching 70 the device to any desired support.

2. In a keeper for fastening devices provided with tying cords, the combination of a member for holding the cords, supporting means for the holding member comprising 80 a pair of tapering members, a cross bar connecting the lower ends of the tapering members, means passing through the cross bar for attaching the device to any desired support, and means co-operating with the holding member for exerting a substantially uniform binding pressure about the cords. 85

3. In a tie-keeper, the combination of a base, a bolt passing through the base, a nut on the bolt, triangular shaped supports having their smaller ends attached to the base, inclined members mounted between the triangular members, the triangular members being cut away at their larger ends to provide a channel between the inclined members, and means associated with the inclined members for exerting a substantially uniform binding pressure about the cords. 90 95

4. In a keeper for fastening devices provided with tying cords, the combination of 100 a holding member having diverging walls one of which is provided with a slot, a cord attached to one of the diverging walls and adapted to pass around the tying cords of the fastening devices and through the 105 slot, and a weight on the end of the cord.

In testimony whereof I affix my signature.

GEORGE C. SNYDER.
